C. HAMMER.
BAND CATSUP CAP,
APPLICATION FILED OCT. 19, 1918.

1,353,801.

Patented Sept. 21, 1920.

UNITED STATES PATENT OFFICE.

CHARLES HAMMER, OF QUEENS, NEW YORK, ASSIGNOR TO AMERICAN METAL CAP COMPANY, OF BROOKLYN, NEW YORK, A CORPORATION OF NEW YORK.

BAND CATSUP-CAP.

1,353,801.

Specification of Letters Patent. Patented Sept. 21, 1920.

Application filed October 19, 1918. Serial No. 258,881.

To all whom it may concern:

Be it known that I, CHARLES HAMMER, a citizen of the United States, residing at Queens, in the county of Queens and State 5 of New York, have invented certain new and useful Improvements in Band Catsup-Caps, of which the following is a specification.

This invention relates to a form of closures adapted for receptacles such as bottles, that have a flange on the neck below the top, which closures have means for locking against such flange to secure the closure on the bottle.

15 The object of the present invention is to provide a closure of this character, in which a sealing gasket or washer inside of the cap will be compressed against the top of the bottle, and which closure is provided with 20 a band that will engage the lower edge of the closure, and which is adapted to be bent inwardly at its lower edge against the bottom wall of a flange on the bottle; and which band is provided with a tongue or 25 projection that does not lock but merely contacts with the band, so that on pulling outwardly on the tongue the band will loosen and be removed, to permit the release of the cap for easy removal.

30 In the accompanying drawing showing one embodiment of my invention, Figure 1 shows the cap sealed on a bottle. Fig. 2 shows in elevation, partly in section the cap member of the closure. Fig. 3 shows 35 the band member separate from the cap. Fig. 4 is a plan view of the closure. Fig. 5 shows in section the closure when first placed on the bottle, and also the sealing device. Figs. 6 and 7 are similar views with 40 the closure partly, and completely sealed on the bottle; and Figs. 8, 9 and 10 show a modification.

The closure as shown comprises a cap member 8 of cylindrical form, that may be 45 drawn in a single piece, or otherwise produced as preferred. This cap has the lower edge bent outward and upward to form a kind of bead, or a channel as shown at 9. The other member of the closure comprises 50 a sealing band 10, that is shown as formed of a strip provided with a projecting tongue 12 at the intermediate portion of one end, that will lap the other end portion, but has no locking engagement therewith, see Fig. 3. 55 This band is provided with a flange 13 at

the top that extends inwardly, and is adapted to engage the bead 9 on the cap 8, the band being large enough in diameter to pass down over the cap, as indicated in Fig. 5. As shown the flange 13 is somewhat channel-shaped to engage the channel-shaped bead 9.

The cap and band are so proportioned relative to a bottle 14, provided with a bead 15 having its lower wall substantially transverse to the bottle to form a sealing shoulder, that when the cap is placed on the bottle, and contains a gasket 16, the cap will not reach down as far as the flange 15. The band 10 will engage the cap and project down around the flange 15, as shown in Fig. 5. Upon applying pressure on top of the cap the gasket will be compressed between the cap and the top edge of the bottle, see Fig. 6. The cap and also the band will move downwardly, whereby the band will have its lower edge portion project downwardly beyond the bead 15, as shown in Fig. 6, and the band will be brought into close engagement with the bead on the cap. While being held in this position by the 75 chuck 17, suitable bending means are caused to engage the projecting edge of the band to press it inwardly, as shown at 18 in Figs. 6 and 7. This will cause the band to be bent inwardly at a right angle and engage the 80 lower wall of the flange 15, as shown in Fig. 7, whereby the cap and band will be securely held in sealing position.

The tongue 12 of the band that simply laps without engagement, can be grasped by 90 the user and pulled outwardly to unwind the band that will loosen it from the flange, and also from the cap as it unwinds. By this means the band can be entirely removed from the cap and bottle, and the cap is free 95 to be taken off of the bottle. While the cap and band are shown as substantially separate members, they can be made to be locked together prior to placing on the bottle.

In Fig. 8 I show a band 19 having the 100 flange 20 in the form of a closed bead bent inwardly. In Fig. 9 the cap 7 shows a flange 21 on the bottom that is bent over inwardly and forms a closed bead with the raw edge concealed. These two members are shown 105 assembled in Fig. 10, previous to application to the bottle, which is done in the same manner as set forth, by bending in the lower edge of the band 19. Means for applying this closure to the bottle as set forth in 110

claim 3 are not claimed herein, but form subject matter of an application Serial No. 391625 filed June 25th, 1920.

What I claim is:—

- 5 1. As an article of manufacture, a closure formed of a cup-shaped cap having an external bead or rim at the extreme lower edge, and a strip bent to form a ring with a flange on the upper edge that projects inwardly
- 10 10 and engages the cap at the bead portion, which band has an extension on one end at the intermediate portion in the form of a tongue that laps the other end of the ring strip, such ring being arranged to have the lower edge bent inwardly against the lower wall of a bottle flange, whereby to lock the closure securely on the bottle and which band is adapted for easy removal by outward pull on the band tongue.
- 15 15 2. The combination with a bottle provided with an annular flange spaced below the top, of a closure formed of a cup-shaped cap having the lower edge bent outwardly and upwardly to form an open channel adjacent said flange, and a sealing band in the form of a ring having a projecting tongue on one end of the band that laps the other end of the band, the band having the upper edge bent inwardly and downwardly to
- 20 20 form an open channel that engages the said cap channel portion to removably retain the

cap on the bottle, with the lower edge of the band bent inwardly around the bottle flange at its lower wall, whereby the band is adapted for easy removal by outward pull on its 35 tongue, and separation of the engaging channel portions of the band and cap.

3. The method or process of applying a cap closure to a bottle provided with an annular flange some distance below the top, 40 that consists in applying a relatively deep cup-shaped closure that has its lower edge extending outwardly and upwardly to form a channel which receives a sealing band having its upper edge turned inwardly and downwardly to engage such channel, and thereupon engaging the said closure by an annular sealing device that will apply a downward pressure on the upper part of the said band flange, and which member also 45 exerts a downward yielding pressure on the top of the closure, and thereupon applying pressure inwardly on the lower band portion projecting below the flange while maintaining the said downward pressure on the cap 50 and band portions, to bend the band beneath the flange and secure the closure to the bottle.

Signed at New York city, N. Y., on Oct. 17th, 1918.

CHARLES HAMMER.
